RUBBER HEEL

Tiemen van der Veen, Amsterdam, Netherlands

Application May 22, 1946, Serial No. 671,514
In the Netherlands November 27, 1940Section 1, Public Law 690, August 8, 1946
Patent expires November 27, 1960

4 Claims. (Cl. 36—70)

1

My present invention relates to rubber heels and more particularly to heels provided with means for preventing splashing when walking on a wet street.

It has already been proposed to provide rubber heels with sponge fillings for absorbing moisture. Devices of this type are described for instance in the German Patents Nos. 505,626 and 548,974.

Such known rubber heels are equipped with ducts connecting a sponge filling arranged within the body of the rubber heel with the front and rear faces of the heel. These arrangements have the great disadvantage that during walking water absorbed by the sponge filling is ejected through the openings in the rear face of the heel, thus causing splashing.

Accordingly, it is an object of my present invention to provide rubber heels which prevent splashing.

Another object of my present invention consists in a rubber heel provided with means which are adapted to absorb the water on a wet street during walking and to eject the same in such a manner as to avoid splashing.

With the above objects in view, my present invention mainly consists in a rubber heel provided with at least one duct extending in the body of the heel from the bottom face to the front face thereof. Preferably, this duct or ducts are filled with a water absorbent spongy material extending from one end of each duct to the other end thereof.

With a heel construction of the above described type splashing is entirely avoided; this is due mainly to the absence of openings on the rear face of the heel.

In accordance with a preferred embodiment of my present invention, I arrange the duct so that it extends in the heel body parallel to the bottom face of the heel and opens in the front face of the heel; such a duct is combined with at least one hole connecting it with the bottom face of the heel.

In certain cases I have found it advisable to shape the duct within the heel so as to form a flat cavity within the heel body which is arranged parallel to the flat bottom face of the same and slightly smaller than this bottom face. This flat cavity is connected with the front face of the heel by a horizontal slot which is parallel to the bottom face of the heel and reaches almost from one side face of the heel to the other side face thereof. This flat cavity is connected with the bottom face by at least one opening of the type described above.

2

At least one of the openings connecting the cavity within the heel body with the bottom face thereof is arranged near the rear face of the heel. Preferably, I arrange one or two additional openings in the bottom face at substantially equal distance from the front face and rear face of the heel. All these openings extend from the bottom face of the heel body to the cavity within the same.

10 The novel features which I consider as characteristic for my invention are set forth in particular in the appended claims. The invention itself, however, both as to its construction and its method of operation, together with additional 15 objects and advantages thereof, will be best understood from the following description of specific embodiments when read in connection with the accompanying drawings, in which:

Fig. 1 is an elevational section through a heel according to my present invention, along line 1—1 of Fig. 2; and

Fig. 2 is a bottom view of the heel shown in Fig. 1, seen in direction of arrow 2 of Fig. 1.

As shown in Fig. 1, my new rubber heel 9 is attached to a leather heel in the usual way. The rubber heel 9 itself has the conventional outer shape, i. e. it has a bottom face 5, a front face 3, a rear face 4 and two side faces 10.

In accordance with my present invention, I 30 provide within this rubber heel 9 a cavity 2 which is relatively flat and arranged parallel to the bottom face 5. As indicated in Fig. 2 by dotted lines, this flat cavity 2 is almost as large as the bottom face 5 of the heel and is connected with the front face 3 by means of the slot 7 extending almost from one side face 10 of the heel to the other side face 10 thereof.

The cavity 2 is connected with the bottom face by means of three holes, namely the hole 6 arranged near the rear face 4 of the heel, and the two holes 6' arranged at substantially equal distance from the rear face 4 and front face 3 of the heel. As clearly shown in Fig. 1, the walls of the holes 6 are inclined, i. e. the holes 6 and 6' are wider at their outer ends than at their inner ends; this is done for the purpose of facilitating entrance of water through these holes.

The cavity 2 and the holes 6 and 6' are filled with a water absorbent spongy material 8 as 50 clearly shown in the drawing.

My improved rubber heel of the type described above prevents splashing in the following way:

When a person walking with shoes equipped with rubber heels of the above described type 55 sets the foot down, first only the rear edge 11

of the heel touches the ground. During further walking movement the heel turns about this edge until the entire heel bottom 5 is in contact with the ground.

During such turning movement of the heel, water located in the path of the bottom face 5 of the heel will be sucked up by the spongy material 8 in the holes 6, 6' and conveyed by the same through these holes into the cavity 2 where it is retained within the spongy material 8 arranged within the cavity 2.

When, during further walking movement, the entire bottom face 5 of the heel touching the ground is compressed by the weight of the walking person, the cavity 2 within the heel is compressed too, whereby the water absorbed by the spongy material 8 within this cavity will be ejected through the slot 7 into the space under the shank of the shoe. It is evident that such ejection of water cannot cause any splashing which might reach the upper part of the shoe or the garments of the walking person.

During further walking movement, the shoe is turned around the front portion of the sole and thereby the heel is lifted from the ground. This causes the water around the heel to flow under the same into contact with the bottom face 5 of the heel. This water is then absorbed by the spongy material 8 which due to its compression was freed from water contained therein. Thus, the water flowing under the heel during lifting of the same is completely absorbed and cannot cause splashing.

It will be understood that each of the elements described above, or two or more together, may also find a useful application in other types of rubber heels differing from the types described above.

While I have illustrated and described the invention as embodied in rubber heels, I do not intend to be limited to the details shown, since various modifications and structural changes may be made without departing in any way from the spirit of my invention.

Without further analysis, the foregoing will so fully reveal the gist of my invention that others can by applying current knowledge readily adapt it for various applications without omitting features that, from the standpoint of prior art, fairly constitute essential characteristics of the generic or specific aspects of this invention, and, therefore, such adaptations should and are intended to be comprehended within the meaning and range of equivalence of the following claims.

What I claim as new and desire to secure by Letters Patent is:

1. A rubber heel comprising in combination a rubber heel body having a bottom face and a front face; at least one duct extending in said heel body substantially parallel to said bottom face and opening in said front face; at least one hole connecting said duct within said heel body

with said bottom face of said heel body; and a water absorbent sponge member arranged within said duct and said hole or holes and completely filling the same.

5. 2. A rubber heel comprising in combination a rubber heel body having a flat bottom face and a front face; a flat cavity arranged within said rubber heel body parallel to said flat bottom face and being slightly smaller than said bottom face; and extending to said front face; at least one hole connecting said flat cavity with said bottom face of said heel body; and a water absorbent sponge member arranged within said flat cavity and extending to said front face and said bottom face of said heel body.

20 3. A rubber heel comprising in combination a rubber heel body having a flat bottom face, a front face and a rear face; a flat cavity arranged within said rubber heel body parallel to said flat bottom face and extending from said front face almost to said rear face; a hole arranged near said rear face of said rubber heel body and connecting said cavity within said rubber heel body with said bottom face thereof; and a water absorbent sponge member arranged within said flat cavity and said hole and extending to said front face and said bottom face of said rubber heel body.

25 4. A rubber heel comprising in combination a rubber heel body having a flat bottom face, a front face and a rear face; a flat cavity arranged within said rubber heel body parallel to said flat bottom face and extending from said front face almost to said rear face; a hole arranged near said rear face of said rubber heel body and connecting said cavity within said rubber heel body with said bottom face thereof; at least one additional hole arranged in said bottom face of said rubber heel body at substantially equal distance from said rear face and said front face thereof and connecting said flat cavity within said rubber heel body with said bottom face thereof; and a water-absorbent sponge member arranged within said flat cavity and said holes and extending to said front face and said bottom face of said rubber heel body.
